UNITED STATES PATENT OFFICE.

FREDERIC W. C. SCHNIEWIND, OF NEW YORK, N. Y.

COKE-OVEN AND DOOR THEREFOR.

976,935.

Specification of Letters Patent. Patented Nov. 29, 1910.

Original application filed October 24, 1907, Serial No. 398,904. Divided and this application filed June 6, 1908, Serial No. 437,042. Renewed October 22, 1910. Serial No. 588,540.

To all whom it may concern:

Be it known that I, FREDERIC W. C. SCHNIEWIND, a citizen of the United States of America, residing in the city, county, and State of New York, have invented a certain new and useful Improvement in Coke-Ovens and Doors Therefor, of which the following is a true and exact description, reference being had to the accompanying drawings, which form a part thereof.

The present invention relates to the construction and arrangement of the coking retorts or chambers of coking ovens and particularly to the construction and arrangement of the removable top wall portions or doors through which the retorts are charged.

This application is filed as a division of my prior co-pending application 398,904 filed October 24, 1907, and covers specifically one of the forms of apparatus disclosed and claimed generically in my said prior application.

One object of the invention generically claimed in my said prior application and attained with the apparatus specifically claimed herein is the possession of a simple and effective oven door construction so arranged that when necessary it can be readily removed and can be readily put back and sealed in place, and which when sealed in place serves to effectually close the doorway against the air or gas leakage and to insulate the coking chamber against heat loss.

A second object is the provision of a suitable follower which is preferably formed by or connected to one of the doors of the coking retort and which is arranged to bear against the coking body or charge during the coking operation and thereby improve either the coke formed or the volatile products recovered, or preferably to improve both the coke and the volatile components of the coking operation. The follower may improve the coke by compressing the charge during the coking operation and thereby produce a denser and more uniform grade of coke. By serving as a displacing agent the follower may prevent the formation of spaces in the hot portions of the retort in which the volatile products would otherwise collect and stagnate more or less. The "cracking" of the hydro-carbons resulting from their long exposure to high temperatures, which is thus avoided, results in a ma-

terial increase in the value of the volatile products recovered in the coking operation.

The specific object of the present invention is the provision of a top door or removable top wall construction particularly adapted for use with coals which change materially in bulk as they are converted into coke, though this construction may be used with any kind of coal.

The top door construction by which I obtain this specific object comprises an outer sealing member and an inner follower member movably connected to the sealing member and filling the upper end of the coking chamber and free to rest on the charge and rise or fall with it as the charge expands or shrinks during the coking operation.

The various features of novelty which characterize the invention are pointed out with particularity in the claims annexed to and forming a part of this specification. For a better understanding of the invention, however, reference may be had to the accompanying drawings and descriptive matter in which apparatus in which the invention may be embodied are illustrated and described.

Of the drawings: Figure 1 is a sectional elevation of a coke oven through a coking chamber having doors at the top and bottom. Fig. 2 is a section taken transversely to the section shown in Fig. 1 and between the ends of the coking chamber.

In the drawings: A represents the fire-brick walls of the coke oven structure, and A' a masonry inclosing shell. The masonry may be supported in any suitable manner, though preferably by the metal floor beams A² and columns A³. In the walls A are formed one or more coking retorts or chambers B, each of which in the form shown is long and deep but narrow. The retorts may be heated in any suitable manner, as by heating flues B' at the sides of the retorts, which may be connected at their upper and lower ends with burner chambers B² and with the passages B³ running to regenerative chambers, as described and claimed in my co-pending application, Serial No. 398,902, filed October 24, 1907.

The retorts B in the structure shown are charged with coal through their upper ends, and the coke formed is discharged through the lower ends of the retorts. On this account each retort is provided with a remov-

able top wall or door, and a removable bottom wall or door. The top wall or door comprises a body C of heat-resisting and insulating material, such as hollow fire-brick, tile or the like, and a metal cap piece or sealing member C'. The member C' is provided with a depending flange portion C⁴ which enters telescopic fashion in the space, groove or trough formed between the upwardly extending ribs E' formed on the metal rim member E which surrounds the upper end of the retort B. The member C⁴ and the member E and its ribs E' thus unite to form a seal which may be packed with any suitable material. Longitudinal grooves are formed in the sides of the tile forming the body C into which extend the inturned flanges of a metal cap piece C⁵. Rods C⁶ connected to the cap piece C⁵ extend freely 20 through the sealing member C' and have eyes C' at their upper ends for engagement by the operating devices.

The bottom door comprises an inner part D which extends to the upper edges of burner chambers B² and may be substantially like the part C, and an under metal supporting part D' on which the part D rests and may be secured by any suitable means as lugs D² of the part D' entering 30 recesses in the tile or brick part D. The bottom door, however, is provided with a flange D³ which with the body of the member D' and the bottom plate D⁴ form the trough into which the flange F' of the rim F projects to form the seal. Each bottom door 35 may be held in place by any suitable means, as for instance by the pinion actuated bolts or rack bars F² sliding in guides F³ to engage and disengage the ends of the yokes F⁴ 40 secured to the under side of member D'.

The mechanism for raising and lowering the top and bottom walls or doors in charging and discharging the retort forms no part of the present invention and for that reason 45 is not illustrated or described herein.

In operation, when the oven is "around," i. e. the coke in it is ready to be discharged, the lower door is removed and the coke formed is discharged in a proper manner; 50 the door is then replaced and the seal completed by inserting the packing material in the space between the ribs D². The upper door is then removed and the charge of coal to be coked is inserted and compacted up to 55 the desired level. After this is done the cover or door is replaced and the seal is completed by the insertion of the packing material between the ribs E'.

Some coals contract in coking while others expand, the change in bulk depending on the amount of volatile matter in the coal. Coals with less than twenty per cent. of volatile matter expand materially, while coals with thirty to thirty-five per cent. of volatile 65 matter shrink very considerably.

The specific construction disclosed will operate satisfactorily with any degree of expansion or contraction of the charge which is met in practice. The amount of coal put into the retort at each charging operation, 70 however, depends on the character of the coal. Preferably the retort should not be filled with expanding coal to such a height that the expansion of the charge will cause the cap C⁵ to engage and lift the sealing 75 member C'. With shrinking coal the retort may be charged to the maximum extent which will permit the top door to be put in place and the proper seal formed between members C' and E. The telescopic flanges 80 at the top and bottom need overlap only enough to form an effective seal. As the overlapping flanges need not move after the initial adjustment the seal packing may be formed of any suitable liquid, pulverized 85 material, such as sand or coal dust, lime, clay or other luting material. The operation of packing the seals is a simple and inexpensive one. The sealing troughs can be readily cleaned after each seal breaking 90 and the masonry walls are not injured by the adherence to them of luting material, as has frequently been the case with oven door constructions heretofore used.

In the oven shown the volatile products 95 escape to suitable reservoirs or receptacles through the inclined vents B⁵ in the end walls of the retort, the lower vents being protected against clogging by the coal by means of the forebays B⁶. As the cover 100 body C rests on the top of the charge and practically fills the upper end of the retort there is no space in the retort in which the volatile products can collect, consequently as they are given off from the coal, they pass 105 at high velocity along the walls of the retort to the escape vents and are not overheated.

As shown, the movable follower portion 110 or body C of the upper wall or door is made of substantial depth or thickness measured in a vertical direction, and in practice I make the vertical dimension of the follower C great enough so that when the retort is 115 properly charged, the upper portion of the body C will be maintained throughout the entire coking operation at a level not below that of the top passages B³, so that while some volatile products may accumulate above the body C, such accumulation is well above 120 the hot part of the retort walls which terminates practically with the level of the passages B³. The weight of the follower portion of the top door should of course be so proportioned as to impress the right pressure 125 on the charge with the consequent avoidance of spongy coke.

In addition to the advantages pointed out above, it will be observed that the doors are mechanically well constructed to serve as the 130

movable walls of a horizontally elongated retort of large capacity which is charged through its upper ends along its entire length and from which the coke formed may 5 be moved out in an unbroken cake.

Having now described my invention, what I claim as new and desire to secure by Letters Patent, is:

1. A door for a coking retort open at the 10 top, said door comprising an outer sealing member and an inner member movably connected thereto, formed of heat resisting material and adapted to fill the upper end of the retort and to rest on and rise and fall 15 with the coking body during the coking operation, said inner member being of such vertical depth that its upper edge may be maintained throughout the coking operation above the highly heated portions of the retort walls.
2. A door for a coking retort open at the top, said door comprising an outer sealing member and an inner member of heat resisting material adapted to fill the upper end of the retort and rest on and rise and fall with the coking body during the coking operation, and rods connected to said inner body 20

and passing freely through said outer member for engagement by operating devices, said inner member being of such vertical 30 depth that its upper edge may be maintained at all times above the highly heated portions of the retort walls.

3. In combination a coke oven structure having a coking chamber and a trough running around the upper end of said chamber and a removable top wall for said chamber comprising an upper sealing member having a flange entering said trough and a lower follower partition filling the upper end of 35 said chamber and movably connected to said sealing member whereby said follower member may bear on the top of the charge during the charging operation and is free to rise or fall with it as the charge expands or shrinks, 40 said inner member being of such vertical depth that its upper edge may be maintained at all times above the highly heated portions 45 of the retort walls.

FREDERIC W. C. SCHNIEWIND.
